United States Patent

Des. 241,890
Patented Oct. 19, 1976

241,890

SOCK

William E. Cline, Drexel, N.C., assignor to Drexel
Knitting Mills Company, Drexel, N.C.

Filed Mar. 25, 1975, Ser. No. 561,780

Term of patent 3½ years

Int. Cl. D2—04

U.S. Cl. D2—332

The figure is a side elevational view of a sock, showing my new design, it being understood that the opposite side view is identical.

I claim:

The ornamental design for a sock, substantially as shown and described.
